UNITED STATES PATENT OFFICE.

JOSEPH BENNOR, OF MACON, GEORGIA.

TURPENTINE-STILL.

SPECIFICATION forming part of Letters Patent No. 785,469, dated March 21, 1905.

Application filed August 11, 1904. Serial No. 220,310.

To all whom it may concern:

Be it known that I, JOSEPH BENNOR, a citizen of the United States, residing at Macon, in the county of Bibb and State of Georgia, have invented certain new and useful Improvements in Turpentine-Stills, of which the following is a specification.

This invention relates to that class of turpentine-still wherein turpentine and other products are obtained from wood by subjecting the wood to the proper degrees of heat.

The object of the invention is to provide a simple and efficient apparatus by means of which the distillation of turpentine and other products from wood may be more efficiently and economically effected than has been heretofore attained.

With this object in view the invention consists in the novel construction and combinations of parts, which will be hereinafter fully described and claimed.

In the drawings, Figure 1 is a plan view of the improved apparatus. Fig. 2 is a vertical section, as on the line 2 2 of Fig. 1, enlarged. Fig. 3 is a similar section as on the line 3 3 of Fig. 1. Fig. 4 is a longitudinal vertical section of a modified form of the apparatus. Fig. 5 is a similar view of another modified form of the apparatus. Fig. 6 is a transverse vertical section of the form shown in Fig. 5.

1 designates a receptacle or steam-drum, and 4 a pipe leading thereto from any suitable source of steam-supply. The pipe 4 opens into a centrally-arranged chamber 5, which extends into the drum 1 from the rearward end thereof. The inner vertical wall of the chamber 5 is provided with a series of perforations 6, and the circumferential wall 7 of the chamber 5 is made tapering, as shown, for a purpose hereinafter explained. The forward end of the drum is provided with a hinged door 8, by means of which access may be readily had to the interior of the drum. A suitable catch 9 and bolts 9^a are provided to hold the door in place when closed, and interposed between the door 8 and the end of the drum 1 is a gasket 10 to insure a steam-tight joint.

Arranged within the lower part of the drum

1 is a trackway 11, which is adapted to receive a cylindrical charging-shell 12 in the form of a truck provided with carrying-wheels 13, which support the shell upon the trackway 11. The shell 12 is adapted to receive the pieces or chips of pine or other wood from which the turpentine and other products are to be distilled. The ends of the charging-shell 12 are closed by removable heads 14, which are provided with perforations 15 and flanges 16, as shown. The flanges 16 are fitted to the interior of the shell 12 and when placed therein and given a slight turn are held in place by bayonet-joints 17. By referring to Fig. 2 it will be seen that the rearward end of the charging-shell extends slightly beyond its head 14 and fits snugly around the tapering wall 7 of the chamber 5, thereby providing a practically steam-tight joint.

Leading from the forward end of the drum 1 is a pipe 18, which terminates in a condenser 19, which may be of any well-known construction. The pipes 4 and 18 are provided with controlling-valves 20 and 21, respectively, and the drum 1 is provided with a suitable pressure-gage 22 and a safety-valve 23.

From the foregoing it will be seen that when the valves 20 and 21 are open the steam passes from the pipe 4 into the chamber 5, then through the perforations 6 and into and through the charging-shell 12, and then out through the pipe 21 and condenser 19, the union between the rearward end of the charging-shell 12 and the tapering wall 7 of the chamber 5 preventing the passage of the steam into the drum 1 without first passing through the charging-shell 12 and the wood contained therein.

Terminating slightly in advance of the door 8 and in line with the trackway 11 is a trackway 24, which leads to a source of wood-supply and which is provided with a branch trackway 25, leading to a point of discharge for the used wood. The end of the trackway 24 adjacent to the door 8 is provided with a hinged section 26, which when raised permits the door 8 to be opened and closed and which

when lowered after opening the door registers with the trackway 11 and forms a connection between the trackways 24 and 11.

In practice it is intended to employ a number of the charging-trucks 12 to the end that while the contents of one truck are being subjected to steam within the drum 1 other trucks may be run upon the trackway to the discharge-station and to the source of wood-supply for the purpose of discharging the used wood and refilling the truck with fresh wood.

The operation of the apparatus may be briefly described as follows: Assuming that the door 8 is closed and that a truck 12 charged with fresh wood is within the drums 1, the valves 20 and 21 are opened and the steam rushes through the wood contained in the truck 12 and out through the pipe 18 to the condenser 19. The action of the steam upon the wood vaporizes the turpentine and other products contained therein, which pass with the steam to the condenser 19, where they are recovered in the usual manner. During the process just described another charging-truck 12 is run upon the trackway to the source of wood-supply. One of the end heads 14 is then removed and a charge of fresh wood is introduced to the truck, the removed end head is replaced, and the truck is run upon the trackway to a position near the door 8 of the drum 1. After the turpentine and other products are distilled from the contents of one truck within the drum 1 the valves 20 and 21 are closed, the door 8 is opened, the section of trackway 26 is lowered, and the truck within the drum 1 is run upon the trackway to the point of discharge. Immediately following the removal of the truck from the drum the truck containing the charge of fresh wood is run into the drum until its end fits snugly around the tapering wall of the chamber 5. The section of trackway 26 is then raised, the door 8 is tightly closed, the valves 20 and 21 are opened, and the process of distillation is carried on as previously explained. Thus it will be seen that by the construction and operation hereinbefore described very little time and heat will be lost in removing a truck containing used wood from the drum 1 and replacing it with a truck containing fresh wood.

If desired, the process of distillation may be effected by the application of heat to the exterior of the drum 1, in which event I employ the construction shown in Fig. 4, wherein a fire-box 30 is provided below the drum 1 and the latter is walled in, as shown, thus causing the products of combustion to pass entirely around the drum 1 in passing to the stack 32.

In Figs. 5 and 6 I have shown a modified form of the invention wherein the supporting-wheels 13^a for the charging-shell 12^a are jour-

naled in the drum 1^a, in which event the trackway 11 would be dispensed with and also the wheels 13, carried by the charging-shell. These figures also show the rearward end head of the drum 1^a provided with an inwardly-extending annular flange, the inner face 7^a of which is made tapering, as shown, to receive the end of the charging-shell 12^a, and thus provide a practically steam-tight joint.

While I have herein shown and described my invention in a desirable and practicable form, yet I do not limit myself to this particular construction, as the same may be modified without departing from the invention.

I claim--

1. In a turpentine-still, the combination of a steam-drum, a charging-shell adapted to be placed within the drum and comprising an imperforate body portion having end heads provided with openings therein, and means for introducing steam to said shell through the openings in one of its end heads whereby the steam is caused to pass entirely through the shell before entering the drum.

2. In a turpentine-still, the combination of a steam-drum provided on its interior with a hollow tapering portion, a charging-shell having openings in the ends thereof and adapted to be placed within the drum to open into and fit said tapering portion, and means for introducing steam to said drum within the tapering portion, whereby steam is caused to pass through the shell before entering the drum.

3. In a turpentine-still, the combination of a steam-drum provided with an opening therein and on its interior with a hollow tapering portion, a door to close said opening, a charging-shell provided with supporting-wheels and having openings therein and adapted to be moved into and out of said drum, and means for introducing steam to said drum within said tapering portion, whereby steam is caused to pass through the shell before entering the drum.

4. In a turpentine-still, the combination of a steam-drum provided with an opening therein and on its interior with a hollow tapering portion, a door to close said opening, a trackway within said drum, a charging-shell provided with openings therein and supporting-wheels fitted to said trackway and adapted to be moved into and out of said drums, and means for introducing steam to said drum within said tapering portion, whereby steam is caused to pass through the shell before entering the drum.

5. In a turpentine-still, the combination of a drum or receptacle having an opening therein, a door to close said opening, a charging-shell provided with supporting-wheels and adapted to be moved into and out of said drum, said shell comprising an imperforate body portion having end heads provided with openings therein, and means for introducing steam

to said shell through the openings in one of its end heads whereby the steam is caused to pass entirely through the shell before entering the drum.

be moved into and out of said drum and said trackway being arranged to direct said shell 15 to engage and open into said tapering portion, and means for introducing steam within said tapering portion, whereby steam is caused to pass through the shell before entering the drum. 20

In testimony whereof I affix my signature in presence of two witnesses.

JOSEPH BENNOR.
